UNITED STATES PATENT OFFICE.

HALFDAN A. STEEN, OF MILWAUKEE, WISCONSIN, ASSIGNOR TO ALLIS-CHALMERS COMPANY, A CORPORATION OF NEW JERSEY.

TIME-ELEMENT CIRCUIT-BREAKER.

1,030,030.

Specification of Letters Patent. Patented June 18, 1912.

Application filed February 1, 1911. Serial No. 605,869.

To all whom it may concern:

Be it known that I, HALFDAN A. STEEN, a subject of the King of Norway, residing at Milwaukee, in the county of Milwaukee and State of Wisconsin, have invented certain new and useful Improvements in Time-Element Circuit-Breakers, of which the following is a full, clear, and exact specification.

10 My invention relates to time element circuit-breakers.

It is often desirable that a circuit-breaker permit an overload on an electric circuit to continue for a time before causing the interruption of the circuit, as generally electrical apparatus will stand overloads which are not of too long duration. Various circuit-breakers have been devised for accomplishing this. Sometimes they have 20 been arranged so that they cause the interruption of the circuit more quickly on heavy overloads than on light overloads. My present invention is an improvement on devices of this general character. There 25 is a coil responsive to the current or other condition in the circuit, and this coil, upon the occurrence of an overload or other abnormal condition, causes the energization of an electro-magnet, which, when energized 30 for a predetermined time, produces a sufficient movement of certain movable parts to cause the tripping of a circuit-breaker. The time element required for the movement produced by this magnet is obtained by any 35 suitable retarding device, such as a dash-pot, and the parts moved by the electro-magnet may act directly or indirectly to cause the tripping of the circuit-breaker. In the preferred form of my invention the 40 electromagnet operates a switch which controls the circuit of another electromagnet, the latter controlling the tripping of the circuit-breaker. An auxiliary electromagnetic device may be provided, this device 45 under certain conditions assisting the electromagnet acting on said switch.

The various novel features of my invention will appear from the description and drawings, and will be particularly pointed 50 out in the claims.

The two figures of the drawing show diagrammatically two embodiments of my invention, as operated on closed circuit and open circuit respectively.

In the arrangement shown in Figure 1 a 55 three pole circuit-breaker 10 is arranged in the mains 11 of a three phase or a three wire system, and, though biased to open position, may be held in closed position by a no-voltage coil 12 acting on a latch 13. 60 Coils 14, responsive to the current in the system as by being arranged in the mains 11 or some of them, when energized by an overload on the system raise the switch 15 into engagement with the contacts 16 and 17. This closes the circuit of the coil 18 across two mains of the circuit 11, or any other source of reasonably constant voltage, and the coil 18 lifts its core 19, the latter being retarded by the dash-pot 20. If the 70 overload continues and in consequence the switch 15 remains closed sufficiently long, a collar 21 on an extension of the core 19 engages the normally closed switch 22 and raises it from its coöperating contacts, thus 75 breaking the circuit of the no-voltage coil 12 and allowing the spring 23 to release the latch 13 to trip the circuit-breaker 10. The length of time required may be adjustable in any desired manner, as by a rheostat 18^a. 80

In case the overload exceeds a predetermined amount, the coils 14 are energized sufficiently to bend the springs 24 upon which the contacts 16 and 17 are mounted and bring the latter into engagement with the auxiliary contacts 25 and 26. This completes the circuit for the auxiliary solenoid 27, which, when energized, assists the solenoid 18 to raise the core 19. The energization of solenoid 27 diminishes the time required for opening the switch 22 and causing the tripping of the circuit-breaker 10. The amount of such diminution may be adjusted, as by a rheostat 27^a. 90

In the arrangement shown in Fig. 2, 95 there is a two pole circuit-breaker 30 in the mains 31 of a direct current or a single phase alternating current circuit. The circuit-breaker 30 is biased to open position, but when closed is locked closed by means 100 of the latch 32. Upon an overload in the mains 31, the coil 33, connected so as to be responsive to the current in such mains, closes the switch 34 and energizes the solenoid 35 by connecting it across the mains 105 31 or any other suitable constant voltage circuit. The solenoid 35, when energized, begins to raise its core 36 and the normally

open switch 37 carried thereby, the movement of the core and switch being retarded by the dash-pot 38. If the overload on the mains 31 continues long enough, the solenoid 35 finally closes the switch 37, thus completing the circuit of the tripping coil 39, which, acting on the latch 32, moves it to release the circuit-breaker 30 and allows it to open.

10 Many modifications in the precise arrangement shown and described may be made without departing from the spirit and scope of my invention, and all such I aim to cover in the following claims.

15 What I claim as new is:

1. In combination, an electric circuit, a circuit-breaker in said circuit, a coil responsive to electrical conditions therein, a switch which is closed upon sufficient energization of said coil, a pair of consecutively acting coils adapted to be energized upon the complete closing of said switch, a second switch which is operated by said last mentioned coils, means for retarding the 25 operation of said second switch, and a third coil controlled by said switch and controlling the tripping of said circuit-breaker.

2. In combination, an electric circuit, a circuit-breaker therein, a coil responsive to the current in said circuit, a switch which is closed by said coil upon sufficient energization thereof, a pair of consecutively acting coils adapted to be energized upon the complete closing of said switch, means 35 operated by said last mentioned coils and controlling the tripping of said circuit-breaker, and a time-element device for re-

tarding the operation of said last-named means.

3. In combination, an electric circuit, a circuit-breaker therein, a coil responsive to the current in said circuit, switching apparatus operated by said coil, two coils which coöperate when both are energized and which are energized by said switching mechanism when the current in said circuit reaches two predetermined values respectively, means operated by said coöperating coils or either of them when energized for causing the tripping of said circuit-breaker, and a time-element device for retarding the operation of said last-named means.

4. In combination, an electric circuit, a circuit-breaker therein, one or more current coils connected to said circuit, switching apparatus operated by said coils, two coils which coöperate and the circuits of which are closed by said switching apparatus when said current coils carry currents of two predetermined values respectively, a switch which is operated by said two coöperating coils or either of them when energized, means for retarding the operation of said switch, and an electromagnet the circuit of which is controlled by said switch and which controls the tripping of said circuit-breaker.

Milwaukee, Wis., Jan. 25, 1911.

In testimony whereof I affix my signature, in the presence of two witnesses.

HALFDAN A. STEEN.
